UNITED STATES PATENT OFFICE.

JOHN M. HETHERINGTON, OF MANCHESTER, COUNTY OF LANCASTER,
ENGLAND.

APPARATUS FOR CONTROLLING THE GRINDING OF CARDING-ENGINE FLATS.

SPECIFICATION forming part of Letters Patent No. 399,533, dated March 12, 1889.

Application filed August 10, 1888. Serial No. 232,449. (No model.) Patented in England November 24, 1887, No. 16,157.

To all whom it may concern:

Be it known that I, JOHN MUIR HETHERINGTON, a subject of the Queen of Great Britain and Ireland, of the Vulcan Works, Polldard Street, Manchester, county of Lancaster, England, machine-maker, have invented certain Improvements in Apparatus for Controlling the Grinding of Carding-Engine Flats, (for which I have made application for a patent in Great Britain, No. 16,157, dated November 24, 1887,) of which the following is a specification.

My invention relates to the grinding of the flats which are employed in carding-engines in the form of endless chains, as is well understood. On May 28, 1888, I filed in the Patent Office of the United States an application for Letters Patent for an invention having the same object as my present invention. In my said former invention I caused the working-faces upon the flat bar ends to slide in contact with levers or parts during the grinding operation, and I imparted controlled movements to such levers or parts, the object being to obtain the required surface upon the card-face, and at the same time to maintain an exact relation between such card-face and the said working-faces on the flat bar. In my present invention the rails or parts with which the said working-faces are in sliding contact during the grinding are fixed; but I impart movement to the axis of the grinding-roller. The movement imparted to the roller, in addition to its revolving motion, is arranged to be in directions to and fro, or forward and backward, and slightly inclined with respect to the line of movement of the flat while being ground. The length of the linear movement of the roller may be half the pitch of the chain of flats, or thereabout. The parts are so adjusted and regulated in their movements as that the roller moves at about the same speed as the flats and effects the grinding when moving in the direction contrary to the movement of the flat.

I will describe my invention more fully with reference to the accompanying drawings.

Figure 1 represents a front elevation of my improved apparatus, and also so much of a carding-engine as is necessary to render clear

the manner of application of the apparatus. Fig. 2 is a side view of the parts appearing in Fig. 1, the vertical line in Fig. 2 being the dotted line A B in Fig. 1. Fig. 3 shows the other or reverse side of the most important parts which appear in Fig. 1, drawn full size, with the flat ends in section. Fig. 4 illustrates how the to-and-fro movement may be imparted to the grinding-roller without the intervention of a sliding carriage.

60

In Figs. 1 and 2, *a* is a portion of the fixed bend or curved side frame on one side of a carding-engine, *b* is a part of the flexible bend, *c c'* is a part of the chain of flats which slide upon the flexible bend, and *d* is the grinding-roller, all these being ordinary parts of a carding-engine.

65

The grinding-roller bracket *e* is altered in form to suit my purpose. The said bracket is formed with a projection, *e'*, to increase the length of the top of the bracket, and this top is planed to receive a sliding carriage, *f*, in which is formed a bearing for the shaft of the grinding-roller. A corresponding bracket is fixed at the other side of the engine and sustains a sliding carriage which corresponds to the carriage *f*. A bell-crank lever, *g g'*, is fixed upon a rock-shaft, *h*, which extends across the engine from side to side and is mounted to turn in bearings. To carry this shaft, I have provided the ordinary adjustable blocks which carry the grinding-roller brackets with projecting arms, in which the bearings for the shaft are formed.

70

In Fig. 1, *e* is an arm which projects from the adjustable block *e'* and carries one end of the shaft *h*. The outer rounded end of the arm *g* of the said lever occupies the space between the ends of two adjustable screws, *i i*, with which the forked end *f'* of the carriage *f* is provided. The use of these screws is to establish a connection between the end of the lever and the carriage, so that when the lever is vibrated upon its fulcrum the carriage will be moved to and fro, the screws serving as means for adjustment, so that there shall be no backlash or shake in the connection. It is obvious that any other suitable method of connection between the lever and the carriage may be adopted. Upon the other end 75

of the shaft h is fixed a lever corresponding to the arm g and imparting movement in the same manner to the other sliding carriage, in which the other end of the grinding-roller shaft is mounted. It will be seen that when the shaft h is rocked in its bearings the roller d will be moved to and fro in a straight line, both ends of the roller being moved at once and to the same extent, so that the axis of the roller is always at right angles with the flats which are passing below the roller. The arm g' is connected with one end of a spring, g^2 , which tends to draw down the said arm, and thereby to impart the movement in the direction indicated by the arrow in Fig. 1 to the carriages f . This movement is limited by an adjustable screw, g^3 , which is secured on the end of the arm g' and bears upon a stop, e^4 , which is cast upon the arm e^2 . This screw g^3 , by coming in contact with the stop e^4 , insures that the grinding-roller shall always move exactly to the same point when moving in the direction indicated by the arrow. The movement in the contrary direction is derived from a cam-wheel, j , which is fixed upon the shaft j' . This is the ordinary shaft upon which are fixed the two chain-wheels which carry the chain of flats.

In my other invention, hereinbefore mentioned, I have a cam-wheel differing in the shape of its teeth or sections fixed upon the same shaft. The cam-wheel j acts upon a lever, k , which is loosely mounted upon the rock-shaft h . In a slot in the lever k is fitted a stud, which can be adjusted in position by means of a screw, k' , and which carries a bowl, k^2 . The said cam-wheel is provided with teeth all of the same form and corresponding in number to the number of flats which pass the wheel at each revolution, as in the case of my other invention hereinbefore referred to. In the example the cam-wheel has thirteen teeth. Each tooth is shaped to impart the movement in the direction contrary to the indication by the arrow to the roller d and to control the movement imparted by the spring g^2 . The first-named movement is imparted to the roller by the action of the curve 1 upon the bowl k^2 , the controlling action which governs the speed of movement imparted by the spring being effected by the curve 2. The lever k is provided with a short arm, k^3 , in which is an adjustable screw, k^4 , which bears against a projection on the lever-arm g , or vice versa, the latter arrangement, in which the said screw is carried by the projection and bears against the arm k^3 , being that shown in Fig. 1. In the time required for the chain of flats to move a distance equal to the distance from the center of one flat to the center of the next in the chain the roller d will make a double or to-and-fro movement, during which one of the curves 1 will move the bowl k^2 outward from the cam-wheel, thereby moving the lever k , and the arm k^3 , acting upon the lever g , will turn the shaft h in its bearings, and the two carriages f will be slid by the two levers g to the

left in the drawings—that is to say, in a direction contrary to the indication—the return movement to the right being effected by the spring g^2 , as aforesaid. When moving toward the left hand in Fig. 1, the roller is moving in a direction contrary to that of the flats, but when moving to the right the movement is in the same direction as that of the flats. 75

It will be observed that the line of traverse of the roller is not parallel with the line of movement of the flats which are passing below the roller. In fact, it has such relation to the carding-surface on the card-flat as to 80 compensate for the inclination of such surface with respect to the line of movement of the flat. To make this clear, the line of the carding-surface of one of the flats is indicated by the dotted line c^2 in Fig. 3. When 85 each flat is passing the roller and comes within the range of the action of the roller, the working-faces on the ends of the flats slide upon two rails, which I usually make to the same curve as the flexible bend b , upon which 90 the working-faces slide when the flats are at work, as seen at c' in Fig. 1. One of these rails is seen at l in Figs. 1 and 3. The other rail would, of course, be on the other side of the engine. 95

To keep the ends of the flat which is being ground in close contact with the two rails, I employ two levers, m , which are fixed upon a rock-shaft, n , and upon the same shaft is fixed a loaded lever, m' . The said loaded lever, by tending to turn the shaft n in its bearings, causes the levers m to press the flat upward against the two rails l . The rails l , the levers m , the shaft n , and the loaded lever m' are also contained in my said former invention, for which I have applied for Letters Patent. 100

The action of the parts is as follows: In Figs. 1 and 3 the roller has just reached the limit of its traverse in the direction indicated by the arrow, the screw g^3 is bearing upon the stop e^4 in Fig. 1, and the bowl k^2 in the same figure is near the bottom of the space between two teeth in the cam j . At the same time one of the flats is just meeting the grinding-roller, as seen in Fig. 3, the said flat being marked c^2 . The movement of the cam j will now push outward the end of the lever-arm k , whereby the carriages f will be caused to slide in a direction contrary to the indication by the arrow. The flat c^2 will at the same time be moving in the indicated direction—that is to say, in a direction contrary to the movement of the carriages f . During these movements of the grinding-roller and the flat in opposite directions the surface of the flat will be ground by the action of the said roller, which is revolved as is usual. It will be seen that during this sliding movement of the carriages f the roller will be 115 slightly descending toward the flat which is being ground, the rate of such descent being made to compensate for the angular position 120 of the face of the flat with relation to its line 125 130

of movement. When the point of the tooth which has been acting upon the bowl k^2 commences to pass the said bowl, the direction of movement of the carriages f will be reversed, 5 and the grinding-roller will then move in the same direction as the flat, and will at the same time be rising slightly away from the flat, so that by the time the roller has moved back into the position indicated in Fig. 3 the 10 roller will be exactly in position to commence upon the higher edge of the next flat, c^4 , in the chain. By repetitions of these movements the whole of the flats in the chain are successively ground.

15 It is not absolutely necessary that the lateral movement of the grinding-roller shall be on a straight line, as it might be on a curve which would approximate to a straight line.

Fig. 4 shows the roller carried by lever- 20 arms g^5 , which would be acted upon by the lever k k^3 and the cam j , as in the case of the levers g .

Having fully described my invention, I state that what I claim as my invention is—

25 1. The carriage f , carrying the grinding-roller d , the shaft h , and arms g , for sliding the said carriages to and fro, the lever k k^3 , for operating upon the shaft h through the arm g , and the cam j , for operating upon the 30 lever k k^3 , substantially as and for the purpose set forth.

2. The roller d , mounted on the sliding carriage f , the slide at e' on the bracket e , having the described inclination with respect to the rail l upon each side of the carding-engine, in 35 combination with means, substantially as described, for traversing the carriages f to and fro during the grinding action of the roller d upon each flat in the traveling chain c , substantially as set forth. 40

3. The cam-wheel j , the lever k k^3 , the shaft h , and the lever-arms g , one formed with an arm, g' , attached to the spring g^2 , in combination with the sliding carriages f f' , carrying the guiding-roller d , substantially as set forth. 45

4. The grinding-roller d and movable bearings therefor, in combination with the shaft h , arms mounted on said shaft and operating said bearings, the lever k on said shaft and adapted to actuate said arms, and the cam j , 50 engaging and adapted to oscillate said lever, substantially as set forth.

In testimony whereof I have signed my name to this specification in the presence of two subscribing witnesses.

JOHN M. METHERINGTON.
